UNITED STATES PATENT OFFICE.

HENRY SEHER, OF NEW YORK, N. Y.

DESIGN FOR A CANDLE-CUFF.

SPECIFICATION forming part of Design No. 22,368, dated April 25, 1893.

Application filed February 23, 1893. Serial No. 463,488. Term of patent 7 years.

To all whom it may concern:

Be it known that I, HENRY SEHER, a citizen of the United States, residing at New York, in the county and State of New York, have invented and produced a new and original Design for Candle-Cuffs, of which the following is a specification, reference being had to the accompanying drawings, forming part thereof.

This design has for its object to provide a novel and ornamental candle cuff and the leading features thereof reside in a candle cuff having radially projecting ribs and curved ridges extending from said ribs.

The design is illustrated by the accompanying drawings in which—

Figure 1, is a plan view of the cuff. Fig. 2, is a section along xx Fig. 1.

In the drawings the letter A indicates the hole or perforation for the passage of the

candle. From the circumference of this hole 20 project the radial ribs B and curved ridges C extend from said ribs. Between the inner ends of the ribs B are the plain circular fields D.

The design provides a novel and ornamental candle cuff which presents a distinguishing and characteristic appearance to the eye.

What I claim as new, and desire to secure by Letters Patent, is—

The design for a candle cuff, substantially 30 as shown and described.

In testimony whereof I have hereunto set my hand in the presence of two subscribing witnesses.

HENRY SEHER.

Witnesses:

W. M. C. HAUFF,
E. F. KASTENHUBER.
